SPEED SELECTOR WITH DELAYED TEMPERATURE DATUM ADJUSTMENT

John Skellern, Northolt, England, assignor to D. Napier & Son Limited, London, England, a company of Great Britain

Filed May 14, 1957, Ser. No. 659,057

Claims priority, application Great Britain May 14, 1956
5 Claims. (Cl. 60—39.28)

This invention relates to control systems for variable speed gas turbine power units, of the kind in which there is a temperature-sensing device for sensing the turbine inlet temperature and arranged to influence the supply of fuel to the power unit in the event of there being a difference (herein termed "an error") between the datum temperature to which the temperature-sensing device is set and the apparent temperature at the turbine inlet as sensed by the device, the effect on the fuel supply being an adjustment thereof tending to eliminate the error. Such temperature-sensing devices are commonly used in gas turbine power units for ensuring that the turbine is not overheated.

This application is a continuation in part of my pending application #548,506 filed November 22, 1955, now a U.S. Patent #2,802,335 granted August 13, 1957.

In some cases the maximum permissible temperature at the turbine inlet is different at different speeds. In such cases a variable datum temperature-sensing device may be provided, the adjustment of the datum being effected by a speed selector member of the power unit which also adjusts the fuel supply to produce any desired change in speed.

Temperature sensing devices are not instantaneous in their response to changes in the actual temperature being sensed, due largely to the heat capacity of the part that is exposed to the temperature being sensed. Consequently, in the event of the speed selector member being suddenly moved to increase the actual temperature at the turbine inlet and to increase the datum, the actual temperature at the turbine inlet might rise substantially above the new datum by the time the apparent temperature as sensed by the device begins to exceed the new datum and the resulting error between the datum and the apparent temperature causes the device to reduce the fuel supply. Conversely, in the event of the speed selector member being suddenly moved to reduce the actual temperature at the turbine inlet and to reduce the datum, the apparent temperature as sensed by the device might still be above the new datum when the temperature at the turbine inlet had fallen to or below the new datum, and the error between the datum and the apparent temperature would cause the device to operate to reduce the fuel supply below what was actually required to maintain the actual turbine inlet temperature at the new datum. This might in some cases cause flame extinction or stalling of the compressor. These under-corrections and over corrections of the fuel supply by the temperature-sensing device may also cause "hunting" of the fuel regulation.

It is an object of the present invention to minimize or overcome these disadvantages.

According to the present invention, in a control system of the kind specified which includes means actuated by the speed selector member of the power unit for adjusting the datum of the temperature-sensing device in accordance with changes in selected speed of the power unit, a delay device is provided between the speed selector member and the datum adjustment.

In one form of the invention the characteristics of the delay device are such that adjustments of the datum in response to movements of the speed selector member approximately coincide with the response of the temper-

2

ature-sensing device to changes in the turbine inlet temperature resulting from such movements.

Thus, in the event of the speed selector member being moved to adjust the fuel supply to provide a change of speed, the datum of the temperature-sensing device will also be adjusted but more slowly, with a delay corresponding approximately with the delay in the response of the temperature-sensing device, so that although the actual temperature at the turbine inlet will change quickly as a result in the change in the fuel supply while the apparent temperature as sensed by the temperature sensitive device changes at a slower rate, there will not be a material error between this apparent temperature and the datum temperature because the datum temperature will also change at about the same slow rate. By timing the adjustments in the datum to coincide with the changes in the apparent temperature as sensed by the device instead of with the changes in the actual temperature at the turbine inlet, under-corrections or over-corrections of the fuel supply by the temperature sensing device are virtually eliminated.

In another form of the invention the characteristics of the delay device are such that adjustments of the datum in response to movements of the speed selector member lag behind the response of the temperature-sensing device to changes in the turbine inlet temperature resulting from such movements, to provide an acceleration control.

Thus if, during a selected acceleration of the power unit, the actual turbine inlet temperature has attained a particular value, the apparent temperature as sensed by the temperature sensing device has attained some lower value, and the datum setting of the temperature sensing device is at a still lower value owing to its greater time lag, the error between the datum temperature of the temperature sensing device and the apparent temperature sensed by the temperature sensing device will reduce the fuel supply to the engine and so arrest and control the rate of power unit acceleration.

In a control system in which the movements of the speed selector member are transmitted to the datum adjustment through a servo motor it is convenient to incorporate the delay device in the servo motor. For instance, a hydraulic servo motor may be provided with restrictors in the flow passages for the actuating fluid to retard the rate of flow.

The present invention may be incorporated in various type of control system, and may be fitted with various refinements to suit special requirements. For instance, in one form of control system for an aircraft power installation containing a plurality of gas turbine power units provision is made, in the event of failure of a power unit, for the remaining power unit or units automatically to be set to produce an abnormally high emergency power output. This requires the temporary elimination of the influence of the turbine inlet temperature-sensing device of any power unit set to produce the emergency power output. In one form of the invention applied to such a control system the temperature-sensing device influences the supply of fuel to the power unit by means of a bleed valve, and the system includes means whereby the bleed valve can be maintained in the closed position to eliminate the influence of the temperature-sensing device.

The invention may be performed in various ways, and one particular form of gas turbine control system embodying the invention will now be described by way of example with reference to the accompanying drawings in which:

FIGURE 1 is a diagrammatic view of the power unit showing certain elements of its control system; and

FIGURE 2 is a diagrammatic view of the temperature-sensing device for sensing the turbine inlet temperature.

The gas turbine power unit 10 shown in FIGURE 1 is

intended for driving one rotor 11 of a twin rotor helicopter, a second rotor being driven by a similar power unit which is not shown. The power unit 10 comprises a vertically mounted axial flow compressor 12 which draws in air through an inlet 13, compresses this air and discharges it into combustion chambers 14 wherein the air supports the combustion of a metered quantity of fuel injected through burners 15. The hot gases are expanded through a compressor-driving turbine and a power turbine contained in a turbine casing 16 and are exhausted to the atmosphere through ducts 17. The compressor-driving turbine drives the compressor 12 through a shaft 18, and the power turbine drives the rotor 11 through reduction gearing 19 and a shaft 20 equipped with a torque-sensing device 21.

The fuel supplied to the burners 15 is drawn from a tank 63 and delivered by a variable stroke plunger pump 22 through a metering unit 23 and a delivery pipe 24. The metering unit regulates the quantity of fuel delivered to the burners in dependence on the setting of a speed selector member 25 under the pilot's control, and also imparts automatic corrections to compensate for variables which would affect the speed of the power unit, namely the temperature and pressure of the air entering the compressor 12. The speed selector member 25 is connected to the metering unit 23 through a connection 26. If the speed selector member 25 were suddenly advanced to increase the speed of the power unit, the metering unit 23 would permit a large quantity of fuel to pass to the burners which might produce an undesirably high temperature at the turbine inlet. To avoid this possibility an additional control is exercised over the metering unit in response to the turbine inlet temperature as sensed by a mercury-filled bulb 27. The control is effected by means of a temperature-sensing device 28 shown in more detail in FIGURE 2. This device comprises a Bourdon tube 29 connected by a capillary tube 30 to the bulb 27, a lever 31 having a fulcrum 32 and against which the upper end of the Bourdon tube acts, and a half-ball bleed valve 33 against which the free end of the lever 31 bears. The half-ball bleed valve 33 permits metered fuel to bleed off from the delivery pipe 24 through a pipe 54 and back to the inlet side of the fuel pump 22 through a pipe 65 when the apparent temperature at the turbine inlet rises high enough to cause the Bourdon tube 29 to raise the lever 31, and so reduces the supply to the burners 15.

At different speeds of the power unit the maximum permissible turbine inlet temperature for normal operation also differs. Consequently it is necessary for the datum of the temperature-sensing device 28, i.e. the apparent turbine inlet temperature at which the bleed valve 33 opens, to be varied in dependence on the speed of the power unit. This is effected by connecting the speed selector 25 to the temperature-sensing device through a connection 34 which determines the position of the fulcrum 32.

The connection 34 carries a cam 35 which is adjustable by means of a clamp 36. The cam acts on a lever 37 which in turn controls a half-ball valve 38. This valve is mounted in the piston 39 of a follow-up servo motor 40. The space 41 below the piston 39 is in permanent communication with a pipe 42 through which fuel under pressure is supplied, and the space 43 above the piston likewise communicates with the pipe 42 but through a fine restrictor 44 so that fluid can enter the space 43 only slowly. The half-ball valve 38 controls the escape of fluid from the space 43 through a passage 45 and a restrictor 46. The piston area exposed to the space 43 is greater than that exposed to the space 41 so that when the half-ball valve is closed the piston 39 slowly descends. If the selector member 25 is moved to cause the cam 35 to permit the lever 37 to tilt clockwise and so permit the half-ball valve 38 to lift, fluid will escape from the space 43 permitting the piston 39 to

rise by an amount equal to the lift of the half-ball valve 38. Conversely, if the selector member 25 is moved in the opposite direction the valve 38 is closed and since fluid can no longer escape from the space 43 the piston 39 descends until the valve 38 ceases to follow it. A spring 47 interposed between the cam 35 and the lever 37 permits the cam to be moved in advance of the corresponding downward movement of the piston 39 and the valve 38. The movements of the piston 39 are transmitted to the fulcrum 32 through a lever 49 having an adjustable fulcrum 48, and through a rod 50. Adjustable abutments 51 and 52 determine the end positions of the piston 39.

The lever 31 thus constitutes a differential member 15 having three elements, namely the end controlling valve 33, the intermediate point controlled by Bourdon tube 29, and the fulcrum 32, the positions of the last two elements determining the position of the first element.

The arrangement described ensures that in the event 20 of there being an error between the datum temperature to which the temperature-sensing device is set (i.e. the position of the fulcrum 32) and the apparent temperature at the turbine inlet (i.e. the position of the upper end of the Bourdon tube 29) an appropriate adjustment

25 of the metered fuel supply will be effected by the half-ball valve 33. But the apparent temperature at the turbine inlet will differ from the actual temperature at the turbine inlet when operating conditions are changing rapidly, owing to thermal inertia of the bulb 27. Consequently a false adjustment of the fuel supply would occur, accompanied by the undesirable effects previously mentioned, unless the measures contemplated by the present invention are employed. These measures comprise the incorporation of a time delay into the follow-up servo 30 motor 40 by means of the said restrictors 44 and 46. These restrictors are so selected that the movements of the piston 39 in response to movements of the speed selector member 25 are delayed to coincide approximately with the changes in the position of the upper end of the Bourdon tube 29 resulting from changes in the turbine 35 inlet temperature produced by changes in fuel supply caused by the said movements of the speed selector member 25.

Alternatively, by selecting the restrictors 44 and 46 so 45 that the movements of the piston 39 in response to movements of the speed selector member 25 lag behind the corresponding changes in the position of the upper end of the Bourdon tube, the system will provide an acceleration selector as previously explained.

The system also includes a refinement to satisfy a requirement of this particular twin-rotor installation. This requirement is that if one power unit fails the other must be automatically set to produce an abnormally high emergency power output. This entails accepting temporarily an abnormally high turbine inlet temperature. If the said refinement were omitted, the system as so far described would operate to prevent the occurrence of this high temperature which would prevent the desired high emergency power output from being achieved. The refinement

55 operates to put the temperature-sensitive device of one power unit out of action automatically when the other power unit fails. As previously indicated, each power unit transmits its drive through a torque-sensing device 21. In the event of the transmitted torque of one power unit falling to a predetermined value indicative of a failure, the torque-sensing device 21 thereof sends a signal through a connection 53 to actuate an emergency override device 60 of the other power unit. The power unit illustrated has an identical override device 60. The override device 60 comprises a valve 61 actuated by a servo motor 62 controlled through a connection 53A from the torque-sensing device of the other said power unit. On actuation of the servo motor 62 the valve 61 admits fluid under pressure into a pipe 55 leading to a 60 space above a piston 56 to depress this piston and close

the half-ball bleed valve 33 irrespective of the position of the lever 31. The temperature-sensitive device 28 thereupon ceases to have any influence over the fuel supply.

What I claim as my invention and desire to secure by Letters Patent is:

1. A control system for a variable-speed gas turbine power unit, including a fuel metering unit for metering the fuel supply to said gas turbine means for adjusting the supply of metered fuel to said gas turbine, a temperature-sensing device exposed to the turbine inlet temperature, a differential member having three elements the position of one of which is determined by the position of the other two, an operative connection between said one element and said fuel adjusting means, a connection between said temperature-sensing device and another element of said differential member whereby the position of this element depends on the apparent turbine inlet temperature as sensed by said temperature-sensing device, a turbine inlet temperature datum adjusting device, an operative connection between said datum adjusting device and the third element of said differential member, said differential member influencing said fuel adjusting means when there is an error between the turbine inlet temperature datum and the apparent turbine inlet temperature as sensed by said temperature-sensing device, a speed selector member for said gas turbine, a first operative connection between said speed selector member and fuel metering unit, a second operative connection between said speed selector member and said datum adjusting device adapted to adjust the turbine inlet temperature datum in accordance with the setting of said speed selector member, and a time delay device in said last mentioned operative connection for delaying the change in adjustment of said datum responsive to a movement of said speed selector member.

2. A control system according to claim 1 in which said operative connection between said speed selector member and said datum adjusting device includes a fluid-actuated followup servo motor and said time delay device consists of a fluid flow restrictor incorporated in said servo motor.

3. A control system according to claim 1 in which said means for adjusting the fuel supply comprises a bleed valve adapted to be actuated by said differential member, and the system includes over-riding means adapted when operative to hold said bleed valve closed to permit over-fueling irrespective of the position of said differential member.

4. A control system according to claim 1, in which said time delay device has an input member and an output member and which includes means connecting said

speed selector member to said input member whereby said input member moves simultaneously with movements of said speed selector member, and means connecting said output member to said datum adjusting device whereby movements of said output member produce simultaneous movements of said datum adjusting device, said time delay device including delaying means whereby a movement of said input member produces movement of said output member said movements of said output member having a predetermined time delay relationship to said movements of said input member, and the inherent heat capacity of said temperature sensing device provides a delayed response characteristic to changes in said turbine inlet temperature, said delaying means being selected so that said time delay relationship of said time delay device coincides with said delayed response characteristic of said temperature sensing device.

5. A control system according to claim 1, in which said time delay device has an input member and an output member and which includes means connecting said speed selector member to said input member whereby said input member moves simultaneously with movements of said speed selector member, and means connecting said output member to said datum adjusting device whereby movements of said output member produce simultaneous movements of said datum adjusting device, said time delay device including delaying means whereby a movement of said input member produces movement of said output member, said movements of said output member having a predetermined time delay relationship to said movements of said input member, and the inherent heat capacity of said temperature sensing device provides a delayed response characteristic to changes in said turbine inlet temperature, said delaying means being selected so that said time delay relationship of said time delay device lags behind said delayed response characteristic of said temperature sensing device.
